US00D530338S

(12) **United States Design Patent** (10) **Patent No.:** **US D530,338 S**
Winjum et al. (45) **Date of Patent:** **** Oct. 17, 2006**

- (54) **IMAGE FOR A PORTION OF A DISPLAY SCREEN**
- (75) Inventors: **Randall K. Winjum**, Vashon, WA (US); **Charles Cummins**, Seattle, WA (US); **Charles W. Stabb**, Seattle, WA (US); **Jan T. Miksovsky**, Seattle, WA (US); **Vincent L. Paceri**, Redmond, WA (US)
- (73) Assignee: **Microsoft Corporation**, Redmond, WA (US)
- (**) Term: **14 Years**
- (21) Appl. No.: **29/228,372**
- (22) Filed: **Apr. 22, 2005**
- (51) **LOC (8) Cl.** **14-04**
- (52) **U.S. Cl.** **D14/485**
- (58) **Field of Classification Search** 715/500.1, 715/501.1, 526, 530-31, 539, 708, 711, 717, 715/723, 726, 733, 738, 753, 762, 763-4, 715/767-69, 778-82, 788, 790, 793-94, 715/797-8, 802-10, 835-40, 848-856, 862-63, 715/976, 978; 345/757, 782, 848, 852, 850, 345/809, 837, 798, 752, 163, 156, 537, 474, 345/836, 419, 649, 656, 659, 426, 427, 582, 345/428, 440, 660, 634, 902, 418, 629; D14/485-94; D18/24-33; D20/40, 11; D19/6; D21/324-33; 434/43, 38; 382/305; 400/76; 710/5, 73; 707/102, 707/2; 463/32, 16; 717/170; 705/26, 27

(57) **CLAIM**

The ornamental design for an image for a portion of a display screen, as shown and described.

DESCRIPTION

FIG. 1 is a front view of an image for a portion of a display screen showing a first embodiment of our new design; and, FIG. 2 is a front view of an image for a portion of a display screen showing a second embodiment of our new design. The broken line showing the display screen is for illustrative purposes only and forms no part of the claimed design.

FIG. 1

FIG. 2

UNITED STATES PATENT AND TRADEMARK OFFICE
CERTIFICATE OF CORRECTION

PATENT NO. : Des. 530,338 S
APPLICATION NO. : 29/228372
DATED : October 17, 2006
INVENTOR(S) : Winjum et al.

Page 1 of 4

It is certified that error appears in the above-identified patent and that said Letters Patent is hereby corrected as shown below:

Delete Title page illustrating figure, and substitute therefor, new Title page illustrating figure. (attached)

Delete drawing figures 1-2, and substitute therefor drawing figures 1-2, as shown on the attached sheets.

Signed and Sealed this

Twenty-third Day of January, 2007

A handwritten signature in black ink, appearing to read "Jon W. Dudas". The signature is written in a cursive style with a large, stylized "J" and "W".

JON W. DUDAS
Director of the United States Patent and Trademark Office
